UNITED STATES PATENT OFFICE

168,665

MICROPHONE

Ruth Louise Whyte, Chesterton, Ind., assignor to
Du Kane Corporation, St. Charles, Ill., a corporation of Illinois

Application March 27, 1952, Serial No. 19,065

Term of patent 14 years

(Cl. D26—14)

To all whom it may concern:

Be it known that I, Ruth Louise Whyte, a citizen of the United States, residing at Chesterton, in the county of Porter and State of Indiana, have invented a new, original, and ornamental Design for a Microphone, of which the following is a specification, reference being had to the accompanying drawing, forming part hereof.

Figure 1 is a rear elevation of the microphone embodying my new design;

Figure 2 is a side elevation of the microphone;

Figure 3 is a front elevation of the microphone;

Figure 4 is an end view from the top of the microphone;

Figure 5 is an end view from the bottom of the microphone.

I claim:

The new and ornamental design for a microphone, as shown.

RUTH LOUISE WHYTE.
